UNITED STATES PATENT OFFICE.

ARTHUR LOPEZ, OF NEW YORK, N. Y., ASSIGNEE TO THE HAMMOND TYPEWRITER CO.
OF NEW YORK, N. Y., A CORPORATION OF NEW YORK.

CARRIAGE FOR TYPE-WRITING MACHINES.

1,126,644.

Specification of Letters Patent. Patented Jan. 26, 1915.

Application filed August 13, 1912. Serial No. 714,837.

To all whom it may concern:

Be it known that I, ARTHUR LOPEZ, a citizen of the United States of America, residing in New York, in the borough of Manhattan, county and State of New York, have invented certain new and useful Improvements in Carriages for Type-Writing Machines, of which the following is a specification.

13 This invention relates to an improved carriage for typewriting-machines which is made noiseless in its motion by means of antifriction-rollers arranged at the points of support, and to which, by reducing the friction between the carriage and its supports a free and easy motion is imparted; and the invention consists of a carriage for typewriting machines which is provided at its lower part with a grooved longitudinal 15 guide-rail, and antifriction-balls interposed between the same and a grooved longitudinal supporting-rail, a retaining-roller at one side engaging the rack-bar of the carriage, and antifriction-rollers at the upper part 20 of the frame bearing against the upper guide-rail of the carriage.

The invention consists further of certain details of construction which will be fully described hereinafter and finally defined in 25 the claims.

In the accompanying drawings, Figure 1 represents a plan-view of a typewriting-machine and the paper-carriage of the same, partly in section, Fig. 2 represents an end-elevation of the carriage and its supporting parts, Fig. 3, a vertical transverse section on line 3, 3, Fig. 4, a detail end-elevation of the ball-bearing for the lower part of the carriage, drawn on a larger scale, 30 Fig. 5, a vertical transverse section of the upper antifriction-rollers of the carriage, also drawn on a larger scale, and Fig. 6, a detail plan-view of the lower supporting-rail of the carriage and of the ball-bearings 35 for the lower part or bottom of the carriage.

Similar letters of reference indicate corresponding parts throughout the several figures of the drawings.

Referring to the drawings, *f* represents 40 the supporting-frame of a typewriting-machine, more especially of that type known as the Hammond typewriting-machine. To the base-portion of the frame *f* are attached brackets *b*, which support in recesses *b*¹ at 45 their upper parts a longitudinal supporting-

rail *c* on which the lower part or bottom of the carriage is supported. The rail *c* is rigidly secured into the recesses of the brackets *b* by means of pins *c*¹ and clamping-screws *c*², as shown in Figs. 2 and 4. 50 The supporting-rail *c* is provided with a longitudinal groove having inclined sides, on which latter rest the ball-bearings for the lower or bottom portion of the carriage, which are interposed between the stationary 55 supporting-rail *c* and the longitudinal bottom-rail *d*¹ of the carriage *d*. The carriage *d* is made of the usual construction with circular arms *d*² at the ends, a longitudinal connecting-rod *d*⁴ at one side and a square 60 guide-rail *d*⁵ at the upper end of the inner or opposite side. The ends of the connecting-rod *d*⁴ and guide-rail *d*⁵ are attached by means of screw-nuts to the circular arms *d*² at the ends of the carriage. The carriage 65 is moved over its guide-rails by a steel-band *e* which is connected by a link *e*¹ at its end with a pin *e*² on a longitudinal guide-rail *e*³, which latter is attached to the circular end-arms of the carriage and moved 70 along a beveled retaining roller *e*⁴ that turns around a pin *e*⁵ at the upper end of an upright arm *e*⁶ attached to the base-frame *f* of the machine. The opposite end of the steel-band *e* is applied to a spring-drum *g*, 75 the shaft of which turns in bearings of the bottom-frame *f* of the carriage, the spring-drum and steel-band imparting the motion to the carriage during the operation of the typewriting-machine from the right to the 80 left hand side of the machine, while the motion of the carriage toward the right is accomplished in the well-known manner by a hand-lever at the right-hand end of the carriage. At the upper ends of the circular 85 arms *d*² of the carriage *c* are supported the usual guide-rollers *r*, *r*¹ by which the paper is guided to the printing instrumentalities. The guide-rail *d*⁵ at the upper front-part 90 of the carriage is guided along an anti-friction-roller *h* which is supported on an angular bracket *h*¹ attached to the upper portion *f*¹ of the frame *f* of the machine, and which takes up the friction with the 95 side of the guide-rail, while a second anti-friction-roller *h*², which is supported on a fixed pin *h*³ of the upper portion *f*¹ of the frame bears against the opposite side of the upper guide-rail of the carriage and takes 100 up the friction with the same. The anti-

friction-rollers h and h^2 serve to guide the upper guide-rail of the carriage and take up the friction of the same during its reciprocating motion. The bracket h^1 is extended at its upper portion over the graduated upper face of the guide-rail d^5 as shown in Fig. 5, and forms by its pointed end an indicator h^4 by which the position of the carriage is properly located as it is moved from one side to the other of the machine.

Two antifriction ball-bearings are provided for the lower part or bottom of the carriage, and are composed each of an antifriction-ball i and a retainer i^2 having an opening corresponding with the size of the antifriction-ball. The retainers i^1 are formed of flat plates which are connected by a longitudinal rod i^2 , as shown clearly in Fig. 6. The upper portions of the antifriction-balls i are received in a longitudinal groove or raceway i^3 , having inclined sides which raceway is located at the bottom of the guide-rail d^1 of the carriage. Pins i^4 at the ends of the supporting-rail c prevent the moving of the carriage beyond the ends of the bottom guide-rail c when the carriage arrives at either end of its motion. As the carriage is guided at its lower or bottom part by the antifriction-balls i , and at its upper part by the antifriction-rollers h , h^2 , acting on the upper guide-rail d^5 , while its rack-bar e^3 is retained by the roller e^4 , all the movable parts of the carriage are guided on the frame in a frictionless manner, so that thereby an easy-running and perfectly noiseless motion of the carriage is obtained. The other accessories of the typewriting-machine are of the usual construction and act in coöperation with the noiseless carriage in the usual manner.

I claim:

1. In a typewriting-machine, the combi-

nation, with the grooved supporting-rail of the supporting-frame, of a carriage having a bottom-rail guided by ball-bearings on 45 said supporting-rail and having at its front portion an upper guide-rail guided at its opposite sides by horizontally opposite roller-bearings on the supporting-frame.

2. In a typewriting-machine, the combination, with supporting-brackets on the bottom-frame of the machine and a longitudinal guide-rail supported by the same, of a carriage provided at its lower or bottom part with a lower or bottom guide-rail and at its front part with an upper guide-rail, antifriction ball-bearings interposed between the supporting-rail and the bottom guide-rail, and antifriction-rollers supported on the supporting frame horizontally opposite each other and engaging the horizontally opposite sides of the upper guide-bar of the carriage.

3. In a typewriting-machine, the combination, with a lower supporting-rail supported in the bottom-frame of the machine, of a carriage provided with a lower or bottom guide-rail, a rack-bar and an upper or top guide-rail at the front of the carriage, antifriction ball-bearings interposed between the supporting-rail and the bottom guide-rail of the carriage, a retaining-roller bearing on the rack-bar, and horizontally opposite antifriction-rollers supported on the upper part of the frame and forming contact with opposite sides of the upper guide-bar of the carriage.

In testimony, that I claim the foregoing as my invention, I have signed my name in presence of two subscribing witnesses.

ARTHUR LOPEZ.
